PUSH-BUTTON ELECTRIC SWITCH

Norman William Stevenson, Macclesfield, England, assignor to V. & E. Friedland Limited, Macclesfield, England, a British company

Continuation of design applications Ser. No. 69,206 and Ser. No. 69,210, Mar. 12, 1962. This application June 24, 1965, Ser. No. 86,191

Claims priority, application Great Britain Sept. 13, 1961

Term of patent 14 years

(Cl. D26—13)

FIG. 1.

FIG. 2.

FIG. 3.

FIG. 4.

FIG. 5.

FIG. 6.

FIGURE 1 is a perspective view of a push-button electric switch showing one embodiment of my new design;

FIGURE 2 is a rear elevational view of the switch shown in FIGURE 1;

FIGURE 3 is a side elevational view of the switch shown in FIGURE 1;

FIGURE 4 is a perspective view of a modified form of push-button electric switch in accordance with the present design;

FIGURE 5 is a rear elevational view of the switch shown in FIGURE 4; and

FIGURE 6 is a side elevational view of the switch shown in FIGURE 4.

This application is a continuation of each of applicant's

copending design applications, Serial Nos. D. 69,206 and D. 69,210, both filed March 12, 1962, and abandoned subsequent to filing this case.

I claim:

The ornamental design for a push-button electric switch, as shown and described.
